UNITED STATES PATENT OFFICE.

HARRY COMSTOCK, OF MINEVILLE, NEW YORK.

PRIMER-RETAINER FOR DYNAMITE-CARTRIDGES.

1,230,121.

Specification of Letters Patent. Patented June 19, 1917.

Application filed February 6, 1917. Serial No. 146,966.

To all whom it may concern:

Be it known that I, HARRY COMSTOCK, a citizen of the United States, residing at Mineville, county of Essex, and State of New York, have invented certain new and useful Improvements in Primer-Retainers for Dynamite-Cartridges, of which the following is a specification.

This invention relates to those devices designed for retaining the primer and fuse in a dynamite cartridge to prevent accidental detachment of the fuse and primer cap or detonator from the cartridge.

Various devices have been proposed for tying or securing the fuse to the cartridge. One method is the insertion of the cap on the end of the fuse into an opening leading in a general lateral or inclined relation into the dynamite within the shell and tying the fuse to the shell. This method has the disadvantage of the fuse lying along the outside of the cartridge and in contact with the side of the hole; the string or cord is liable to slip off; if the cap is longer than the diameter of the hole, it may become lodged crosswise thereof and if the cartridge is tamped hard in this position, it is liable to explode. The tendency of the tying cord to slip off renders the cap liable to pull out of the cartridge and the tamping may break the cap or cause it to explode.

Another method heretofore proposed is to unfold one end of the paper shell and to insert the cap into a hole made lengthwise of the dynamite. The opened end of the shell is then tied around the fuse by a cord. This method possesses the objection that the cap is easily pulled from the cartridge. The paper shell of a dynamite cartridge is paraffined to render it waterproof; consequently, no matter how tight the cord may be drawn, the fuse readily pulls through the neck of paper at the end of the shell. While this method places the primer or cap in the proper position in the cartridge, the method of anchoring is unstable and therefore unsafe.

Another plan proposed is that set forth in the patent to William W. Jones Number 1097442, May 19, 1914, wherein a retaining cord is inserted in the dynamite and provided with an adjustable device to engage

the fuse. The cap in that construction is inserted from the top or end of the cartridge. While that device satisfactorily anchors the 55 fuse and cap, the very great expense of placing this anchor in the dynamite and the incident increase in the cost of the cartridge is very objectionable and it appears to be impractical to apply the Jones anchoring device in cartridges which are automatically 60 made in large numbers on machines, the practice which commonly prevails at the present day. Such machines introduce dynamite into a large number of paper shells 65 simultaneously and afterward close the open ends of the shells. The introduction of the anchor of the Jones patent has to occur when the dynamite is being packed into the shell, a difficult and expensive operation. 70

To obviate the disadvantages inhering in the methods and devices above set forth, I have provided an improved primer and fuse retainer or anchor adapted to be tied to the fuse to hold it and the cap firmly anchored 75 to the cartridge. In my invention the cap and end of the fuse are introduced into an opening extending inwardly from the end of the cartridge, which is the safest position for both cap and fuse. 80

Within the paper shell, as distinguished from being located within the dynamite, I provide one or more, preferably two, cords which are adapted to be tied to the fuse after the cap has been entered in an opening in the dynamite cartridge. The cords may be embodied as a part of the paper shell during its formation; or they may be inserted inside the paper shell after the latter is complete and before it is filled with dynamite. Dynamite shells are usually formed on spiral wind machines. While the manner of inserting the cords does not enter into the present invention, I may say that they can be arranged to be formed or laid along 85 the shell during its manufacture so that they will extend lengthwise thereof with their ends freely protruding beyond the ends of the shell at the lines of the end folds. If the cords are placed in the shell after the 90 latter has been formed, they may be connected thereto by adhesive or in any other manner. At one end of the shell the ends of the cords are tied together and at the 95

other end they are tied to the fuse after the cap has been introduced into the dynamite and the open end of the shell folded down. A secure anchorage of the fuse and cap is thus provided and there is no possibility of the cap being injured or exploded or the fuse abraded.

I am aware that my invention is susceptible of modification without departing from 10 the principle thereof, and the embodiment thereof hereinafter described and shown in the accompanying drawings is to be considered as illustrative, rather than restrictive, of the scope of the invention.

15 In the drawings:—

Figure 1 is a perspective of the complete cartridge, ready for priming;

Fig. 2 a vertical section, partly in elevation, showing the cap and fuse inserted in the dynamite, the cords tied at one end of the shell and the remaining end of the shell open; and

Fig. 3 a detail perspective of the upper end of the shell, the cords being tied to the 25 fuse.

The paper shell or cartridge 1 may be formed in any manner, but such shells are usually made on the spiral wind tube machine and afterward one of the ends is folded as at 2. The shell is then grouped with others and the dynamite packed into the shell. Subsequently, the previously open end is folded as at 3. The complete dynamite cartridge is supplied to the trade and 35 when the cartridges are to be used, a section of fuse of the desired length is cut and the cap containing fulminate of mercury or other high explosive is crimped, by a suitable tool, on the end of the fuse. The secure- 40 ment of the cap and fuse to the cartridge then follows. As previously explained, earlier well known methods or devices for anchoring the cap and fuse have their drawbacks.

45 In carrying out my invention I provide the paper shell 1 with cords 4 whose ends 5, 5^a project freely from the folded ends 2 and 3 of the cartridge as the latter is delivered to the user. The cords 4 are applied to the shell 1 either when it is being made, or wound, or to the inside of the shell after it has been finished, by securing these cords to the shell in any desired manner, as, for instance, by a suitable adhesive. The cords are applied to the shell before the dynamite 6 is packed into the shell. The anchoring of the fuse does not depend on the location of the cords within the body of the dynamite 6, but, on the contrary, the shell 1 is provided with the cords and the dynamite there- 50 after packed into the shell. If desired, the loose cord ends 5^a may be tied together as at 7 before, or after, the shell is filled with the dynamite, 6, the other ends 5 of the cords being allowed to project freely so that they

will be in that condition when the cartridge is delivered to the user. If desired, however, the loose ends of the cords may remain that way and tied as at 7 by the user.

When the cartridge is to be used, a section of fuse 8 of the desired length is cut off and a cap 9 is crimped on to the end of the fuse in the usual manner. A hole is then made lengthwise of the dynamite 6 and the cap and fuse entered therein as shown in Fig. 2. If desired, the folded end 3 may be opened out before this operation. After the cap and fuse have been inserted, the ends 5 of the cords 4 are tied to the fuse at 10. The fuse and cap are thus securely anchored to the cartridge as they are firmly retained by the cords 4.

A cartridge which has been primed in the manner set forth may be tamped into the blast hole without danger of accidental discharge if ordinary precautions are observed, and there is little likelihood of the fuse and cap pulling out.

Having thus described my invention, what I claim as new and desire to secure by Letters Patent is:—

1. A primed explosive cartridge or shell comprising the shell, an explosive contained therein, a cap or primer, a fuse therefor, and a cord located and anchored between the explosive and the interior surface of the shell, said cord having an end portion tied to the fuse.

2. A shell or cartridge for containing dynamite or other explosive which is provided with a plurality of cords or flexible devices adapted to be secured together across a closed end of the shell and at the other end thereof to be fastened to the fuse after the shell has been loaded and primed, to thereby anchor the loaded and primed shell to its fuse.

3. A primed dynamite cartridge or shell, comprising the shell, the explosive contained therein, a cap or primer embedded in the explosive and provided with a fuse, and cords carried by the shell proper which are secured together across a closed end of the shell and at the other end of the shell have their ends tied to the fuse.

4. As a new article of manufacture, a paper shell or cartridge adapted to be directly loaded with an explosive, having a cord or the like permanently attached to the inner surface of the shell, and provided with a free portion adapted, on subsequent loading of the shell, to be secured to the fuse.

5. As a new article of manufacture, a paper shell or cartridge adapted to be directly loaded with an explosive, having a cord or the like extending the full length of the shell and permanently attached thereto, provided with free tying portions at its opposite ends for the purpose of anchoring the fuse and prime.

6. As a new article of manufacture, a paper shell or cartridge adapted to be directly loaded with an explosive, having a pair of cords or the like extending the full length of the shell and permanently attached thereto, said cords being provided with free

pair of tying portions being adapted to be secured together across the end of the shell, the other pair of tying portions being adapted for securement to the fuse. 10

In testimony whereof, I hereunto affix my signature.

HARRY COMSTOCK.
